UNITED STATES PATENT OFFICE.

ORLANDO R. MYERS, OF QUINCY, ILLINOIS, ASSIGNOR OF ONE-HALF TO ROY H. EWING, OF QUINCY, ILLINOIS.

MAILING-MACHINE.

1,183,755.

Specification of Letters Patent. Patented May 16, 1916.

Application filed July 23, 1915. Serial No. 41,575.

To all whom it may concern:

Be it known that I, ORLANDO R. MYERS, a citizen of the United States, resident of Quincy, in the county of Adams and State 5 of Illinois, have made a certain new and useful Invention in Mailing-Machines; and I declare the following to be a full, clear, and exact description of the same, such as will enable others skilled in the art to which 10 it appertains to make and use the invention, reference being had to the accompanying drawings, and to letters or figures of reference marked thereon, which form a part of this specification.

15 Figure 1 is a side view of the invention as in use. Fig. 2 is a plan view of the invention. Fig. 3 is a central vertical longitudinal section of the same. Fig. 4 is a front view of the same with the movable knife lowered. Fig. 5 is a similar view with the 20 movable knife raised. Fig. 6 is a detail fragmentary sectional view of the guide plate.

The invention has relation to mailing 25 machines or labeling machines for newspapers or periodicals, for pasting thereupon the labels bearing the names and addresses of the subscribers, having for its principal objects the provision of an improved, compact and efficient machine, which will feed and space the labels automatically and eliminate danger of buckling of the labeling strip and of pasting the label upon the paper or periodical out of its proper place, 30 or beyond the margin of the paper.

The machine is designed also for speed and accuracy.

The invention consists in the novel construction and combination of parts, as hereinafter set forth.

In the accompanying drawings, illustrating the invention, the numeral 2 designates the frame of the machine, including a reel casing or drum 3 at one end, a bottom 45 plate 4, side walls 5, 5 and a longitudinal handle 7 overlying a paste box 6 and usually carried by an upturned lug 8 of the drum and a lug 10 of a cross-bar 11 connecting forward uprights 12, 12 of said frame.

50 Upon the forward portion of the bottom plate, adjacent to the paste box, is located a pair of upper and lower feeding rollers 14, 14, having journal bearings in end uprights 15, and close to said rollers and also carried 55 by said end uprights, through the medium

of end enlargements or lugs 15' of the forked rest hereinafter referred to, is the stationary member 16 or jaw of a shearing knife, said member having its upper or knife edge about in line with the joint between the rollers. The end uprights have a bottom connection, resting upon the floor of the main frame and reinforcing the same.

The movable member or jaw 17 of the shearing knife is carried at one end, at 18', by a lateral rock shaft 18, having bearings in extensions 19 of the frame, said knife being normally held in elevated position by suitable means, usually a coiled spring 20 upon the shaft 18, and the movable knife member is pressed in yielding manner horizontally toward the other member by a spring 20', engaged at one end with the shaft 18 and extending substantially parallel with said member. In order to set the movable member accurately with relation to the fixed knife member, the movable member is allowed a slight lateral movement with relation to its rock shaft, and a set-screw 23 is provided, said screw being carried by a lug 24 of the lateral shaft and bearing against the pivotal end portion of the movable member. And in order to insure that the movable member, upon the upward stroke, shall not interfere with the fixed member, a set-screw 22, carried at the free end of the movable member, has engagement with a bumper cam 22' of the frame, to throw said member outwardly at the end of the downward stroke, and to maintain the outthrown position until the member is moved upward past the bottom of the fixed member.

An operating shaft 24' extends transversely of the machine, having bearings in the upper portions of the end uprights, said shaft having a suitable handle 25 and a mutilated gear 26, meshing intermittently with the upper gear 27 of the enmeshed gears 27, 27' upon the shafts of the feed 100 rollers, said shaft 24 having also bevel gear 28, meshing with bevel gear 28' upon the shaft 30' of cam 30, bearing against the upper edge of and operating the movable knife member, said shaft having bearings 105 in a cross-bar 32, connecting the upper portions of the end uprights. Carried also by the end uprights is a forward projecting forked rest, including a slender bar 33 at each side and a cross-bar connecting the 110

lateral bars and carrying the end lugs 15', said cross-bar being located above the bottom of the frame 15² and immediately under the stationary knife member.

5 The paper upon which is imprinted the names and addresses is located in the end drum, upon a transverse shaft 35, and the strip of paper therefrom passes from the reel, under guide rod 36 at the inner lower 10 end of an inclined guide plate 37 overlying the rear portion of the paste-box, said paper strip passing from said rod over the top of the paste roller 38, over a corrugated scraper rod 39 and thence downwardly between the 15 feed rollers and over the stationary member of the shearing knife to the mail matter.

In operation, the longitudinal handle is 20 grasped with the one hand and the forward edge of the frame brought against the pile 25 of mail matter, the forward projecting forked frame resting upon the mail matter and taking the weight of the machine, the feed rollers being located in rear of and the cutting mechanism and forked frame 30 above said forward edge. The labeling strip 39' having been adjusted to position with relation to the paste roller, feed rollers, etc., the operating crank is turned to intermittently operate the feed rollers 35 and raise and lower the movable member of the knife, said movable member having a flat lower surface and acting as a presser-foot to stamp the gummed label to the newspaper or magazine. As each label is 40 cut and stamped to place upon the topmost magazine or piece of mail matter, a helper or boy pulls or jerks the same from under the machine, which is operated continuously to place the labels upon the successive periodicals or newspapers.

It is preferred that the inclined guide plate shall be composed of upper and lower members, suitably secured together and spaced apart at each side for sliding engagement with guides 40. The lower feed roller 45 is provided preferably with bearings in slots 41 of the end uprights, a spring 42 engaging an annular groove of and serving to press said roller upwardly into engagement with 50 the upper roller.

The shaft 35 of the reel is usually split, for the insertion of one end of the label strip, and is provided with a suitable handle 43. The lower feed roller has a plurality of 55 annular grooves 44, to allow sufficient paste to remain upon the label strip for proper adherence. The scraper rod 39 has a plurality of annular grooves therein, for the same reason. A wire device 45 is carried by cross-bar 60 65 of the rest bars 33, and overlies the fixed knife member about centrally thereof, to prevent undue adherence of the label to said member. In order to stop movement of the label strip upwardly with the movable 65 knife member, wire 47 is provided, above

the label strip and carried usually by the end lugs 15'.

What I claim is:—

1. In a mailing machine, a frame, a label reel, a paste roller, feed rollers, a stationary knife, a pivoted presser-foot knife, a rotary operating shaft having bearings in said frame and located above and parallel to the feed rollers, and means in driving connection with said shaft for actuating said feed 70 rollers intermittently to space the labels and for actuating said pivoted knife.

2. In a mailing machine, a frame, a label reel, a paste roller, feed rollers, a stationary knife located adjacent to the joint between 80 the feed rollers, a pivoted presser-foot knife, and hand operated means for actuating said feed rollers intermittently to space the labels and for actuating said pivoted knife, including intermeshing gears upon the feed 85 rollers, a rotary shaft located above and parallel to the feed rollers and having bearings in said frame, a mutilated gear upon said shaft intermittently engaging the upper of said gears, a rotary cam engaging the pivoted knife, and intermeshing bevel gears upon the cam shaft and said rotary shaft, for operating said cam.

3. In a mailing machine, a frame having 90 end uprights and a cross-bar connecting the same, a label reel, a paste roller, feed rollers, a stationary knife, a pivoted presser-foot knife, and hand operated means for actuating said feed rollers intermittently to space the labels and for actuating said pivoted knife, including intermeshing gears upon 100 the feed rollers, a rotary operating shaft located above and parallel to the feed rollers and having a bevel gear and bearings in said uprights, a mutilated gear upon said shaft intermittently engaging the upper of said gears, a rotary cam having a shaft provided with bearings in said cross-bar, and a bevel gear in mesh with the bevel gear upon 110 said operating shaft.

4. In a mailing machine, a frame, a label reel, a paste roller, feed rollers, a stationary knife, a pivoted presser-foot knife, a rotary operating shaft having bearings in said frame and located above and parallel to the feed rollers, means in driving connection with said shaft for actuating said feed rollers intermittently to space the labels and for actuating said pivoted knife, and means 115 for throwing said pivoted knife outwardly at the end of its downward stroke and for maintaining the outward thrown position thereof until it is moved upwardly past the bottom of the stationary knife.

5. In a mailing machine, a frame, a label reel, a paste roller, feed rollers, a stationary knife, a pivoted presser-foot knife, a rotary operating shaft having bearings in said frame and located above and parallel to the feed rollers, means in driving connection 120 125 130

- with said shaft for actuating said feed rollers intermittently to space the labels and for actuating said pivoted knife, and means for throwing said pivoted knife outwardly at 5 the end of its downward stroke and for maintaining the outward thrown position thereof until it is moved upwardly past the bottom of the stationary knife, including a set screw at the free end of the pivoted knife 10 and a bumper cam upon the frame.
6. In a mailing machine, a frame, a label reel, a paste roller, feed rollers, a stationary knife, a pivoted presser-foot knife, a rotary operating shaft having bearings in said frame 15 and located above and parallel to the feed rollers, means in driving connection with

said shaft for actuating said feed rollers intermittently to space the labels and for actuating said pivoted knife, said pivoted knife having slight lateral play upon its 20 pivot shaft, and a set screw upon an extension of the pivotal shaft of said knife and bearing against the pivotal end of the knife to set the same with relation to the stationary knife. 25

In testimony whereof I affix my signature, in presence of two witnesses.
